INVENTOR

Arthur Rogers.

UNITED STATES PATENT OFFICE.

ARTHUR ROGERS, OF BARNESVILLE, OHIO.

DIE.

SPECIFICATION forming part of Letters Patent No. 691,666, dated January 21, 1902.

Application filed July 23, 1901. Serial No. 69,405. (No model.)

To all whom it may concern:

Be it known that I, ARTHUR ROGERS, of Barnesville, in the county of Belmont and State of Ohio, have invented certain new and useful Improvements in Dies; and I hereby declare that the following is a full, clear, and exact description thereof, reference being had to the accompanying drawings, which form part of this specification.

10 This invention is an improvement in the manufacture of "hollow-back" spades, shovels, scoops, &c., and has particular reference to the dies for making or shaping such shovels, &c., from sheet-metal blanks previously 15 cut to proper form for stamping.

The invention consists in the novel construction of the dies by, first, hinging them together, so that the upper die will always close exactly upon the lower die; second, making 20 the upper die very heavy, so that no machinery will be needed to close the die, its own weight being sufficient to effect the shaping of the metal; third, providing such die with a grip to hold the blank during the shaping process, 25 and, fourth, a setting-plate for the blanks.

The accompanying drawings illustrate the die, such as used for forming hollow-back shovels or scoops.

Figure 1 is a side elevation of the die closed; 30 Fig. 2, a top view thereof opened, and Fig. 3 a longitudinal sectional view through Fig. 1.

Referring to the drawings, A designates the lower or male die, which is formed of heavy cast metal and mounted upon timbers B. Said 35 die has its upper surface formed with a protuberance a, conforming to the desired face or front contour of the shovel, scoop, &c., to be made thereon, and is provided with a groove a', conforming to the contour it is desired to give the shank or tang of the shovel. The lower die also has perforated hinge-lugs a² near its rear edge, as shown. The upper die C is shaped somewhat like, but reversely to, die A, having a concavity to fit the protuberance a of die A and a projecting rib c' to fit the groove a' of die A. It is also provided with hinge-lugs c², adapted to fit snugly between and against lugs a² of die a, and all said lugs are transfixied by the hinge-rod D, 45 as shown. The die C is also provided with a handle C' at its front end, by which it can be

raised, and, if necessary, a powerful leverage can be exerted on handle C', inclosing the die, if the blank should be insufficiently heated or if for other cause the die did not close 55 properly thereon when part C is dropped.

Between the hinge-lugs c² a grip-lever E is pivoted on rod D, said lever having a tooth e on its inner end, which is adapted to bite and hold the front or inner edge of the blank during the pressing thereof, said grip being operated by a hand-lever E', as indicated in the drawings, Fig. 3.

The upper die may be raised by hand or power, it being very heavy, and after a suitable blank H, heated to a red heat, is placed in position over the lower die and held by the grip E the upper die is dropped upon the lower and stamps or forms the blank between the dies into the desired shape. The hinges 70 keep the dies in exact relative position without the employment of other guides.

In order to insure the proper setting of the blanks H, so that the tang or shank of the shovel will be properly formed, the guide-plate F may be used. This is hinged to the supports B in position to be turned down over the grooved end of lower die B after the blank is laid thereon, and on the free edge of this plate are two lugs or guides, which are adapted to embrace the shank or tang h of the blank H between them, as indicated in Fig. 2, and insure the proper location of blank H upon the lower die. The blank is then gripped by lever E and the guide-plate F thrown back 85 out of the way. Then the upper die is dropped and the operation is complete.

Having thus described my invention, what I claim as new, and desire to secure by Letters Patent therefor, is—

1. In a die for forming hollow-back shovels, &c., the combination of the lower die; with the upper weighted die hinged to the lower die at its rear edge, and a grip for holding the blank during stamping thereof.
2. In a die for forming hollow-back shovels, &c., the combination of the lower die; with the upper die hinged to the lower die at its rear edge, a handle for raising said die substantially as described, and a grip for holding the blank during stamping thereof.
3. In a die for forming hollow-back shovels,

the combination of the lower die provided with protuberance a , hollow a' , and lugs a^2 ; with the upper weighted die having recess c rib or projection c' and lugs c^2 and the rod 5 transfixing said lugs and hinging the dies together, substantially as described.

4. In a die, the combination of the lower die provided with protuberance a , hollow a' , and lugs a^2 ; with the upper die having recess c , rib or projection c' and lugs c^2 , the rod 10 transfixing said lugs, and hinging the dies together, the grip-lever pivoted between said lugs, and the blank adjusting or setting plate all substantially as and for the purpose set forth.

5. In a die for forming hollow-backshovels, 15 &c., the combination of the lower die; with the upper weighted die hinged to the lower die at its rear edge, and a grip for holding the blank during the stamping thereof, and the

blank adjusting or setting plate, all substantially as and for the purpose described.

6. In a die, the combination of the lower die provided with protuberance a , hollow a' , and lugs a^2 ; with the upper die having recess c , rib or projection c' and lugs c^2 , the rod transfixing said lugs, and hinging the 25 dies together, the grip-lever pivoted between said lugs, and the blank adjusting or setting plate all substantially as and for the purpose set forth.

In testimony that I claim the foregoing as 30 my own I affix my signature in presence of two witnesses.

ARTHUR ROGERS.

In presence of—

JAMES CASSLELS,
SAMUEL ROGERS.
